UNITED STATES PATENT OFFICE.

HARRY C. TRUESDELL, OF BERLIN, WISCONSIN.

WRISTER.

No. 825,250.

Specification of Letters Patent.

Patented July 3, 1906.

Application filed January 16, 1906. Serial No. 296,381.

To all whom it may concern:

Be it known that I, HARRY C. TRUESDELL, a citizen of the United States, residing at the city of Berlin, in the county of Green Lake 5 and State of Wisconsin, have invented certain new and useful Improvements in Wristers; and I do hereby declare the following to be a full, clear, and exact description of the invention, such as will enable others skilled 10 in the art to which it appertains to make and use the same.

My invention relates to wristers, particularly adapted to be worn within the ends of coat-sleeves.

15 It has for its object to provide a covering for the wrist which may be easily put on and removed and which is of such form as to close the opening in the end of the sleeve.

The invention consists, broadly, of a covering 20 of suitable material, preferably fur, placed around a bent spring. One end of the covering projects beyond the ends of the spring and the other end of said covering forming a pointed extension to the wrister, which is 25 adapted to fit within the portion or fold of the sleeve below the wrist.

The invention also consists of the other features of construction and parts hereinafter described, and more particularly pointed 30 out in the claim concluding this specification.

In the accompanying drawings, illustrating the preferred embodiment of my invention, Figure 1 is a perspective view of the lower end of a sleeve, showing a wrister embodying the invention arranged within the 35 end thereof. Fig. 2 is a detailed view of the wrister alone, and Fig. 3 is a sectional view thereof.

While the preferred embodiment of my invention is illustrated in the accompanying drawings and its construction is described in this specification, the right is reserved to make such changes from the construction shown and described herein as the scope of 45 the claims hereto appended will permit.

Referring more particularly to the drawings, 1 is the covering of fur, which is made in the form of a tube open at the ends for the insertion of the spring 2. Said spring is bent in the form of an oval arranged at the bend 50 with its arms extending therefrom in substantially converging lines to a meeting-point, the ends of said arms being preferably bent out slightly, as at 3, to form abutting surfaces. One end of the tubular covering 55 when in place on the spring projects beyond the ends of said spring and the other end of said covering, as at 4. This projecting end of the covering provides a good bearing for the other end thereof and forms an extension 60 adapted to fit and close the portion of the sleeve below the wrist, where it drops to a pointed fold.

The position of the wrister in the end of a sleeve is shown in Fig. 1, from which the advantages of the extension 4 will be readily observed. The fact that the ends of the spring may be sprung apart and the wrister opened 65 renders the device easy to put on and remove from the wrist.

Having thus described my invention, what I claim as new, and desire to secure by Letters Patent, is—

A wrister comprising a covering tubular in cross-section and a bent spring arranged in 75 said covering, said spring having its upper part rounded and its lower part conical in form, the covering conforming to the shape of the spring and extending beyond the ends of the spring whereby the ends of the latter 80 and its covering serve to form a pointed extension of the wrister, the inner surfaces of the covering, near the ends thereof, held in engagement with each other by said spring.

In testimony whereof I affix my signature 85 in presence of two witnesses.

HARRY C. TRUESDELL.
